UNITED STATES PATENT OFFICE

2,452,556

RADIATOR STRUCTURE FOR AIR HEATING
FURNACES

Frederick W. Eichholtz, Norvelt, Pa.

Application July 17, 1944, Serial No. 545,284

1 Claim. (Cl. 126—99)

1

The invention relates to a heating plant, and more especially to a gravity type home heating apparatus.

The primary object of the invention is the provision of an apparatus of this character, wherein solid or fluid combustible material may be used therein for heating purposes in dwellings or other enclosures, the heating being effected by hot air circulation, the products of combustion traveling in a horizontal direction from an elevated area downwardly, to opposite sides of the combustion chamber or dome, thence upwardly to the rear of the latter, and the spent products finally delivered to a smoke flue or chimney for discharge from the apparatus, thereby assuring maximum combustion with a minimum consumption of fuel, and resultant heating qualities.

Another object of the invention is the provision of an apparatus of this character, wherein it is susceptible of being cleaned without necessity of closing down the fire, the radiation flues being readily and easily accessible for efficient cleaning thereof with dispatch and thoroughness, the apparatus being novel and unique in its entirety, as it promotes high heating efficiency and fuel economy, the radiator arrangement in the apparatus affording greater length of fire or smoke travel, resulting in maximum heat radiation for distribution and a reduction in chimney or discharge flue temperatures.

A still further object of the invention is the provision of an apparatus of this character, which is simple in construction, thoroughly reliable and efficient in operation, strong, durable, most compact, assuring a minimum consumption of fuel with a maximum heating quality, readily and easily controlled, conveniently handled, and inexpensive to manufacture and install.

With these and other objects in view, the invention consists in the features of construction, combination and arrangement of parts as will be hereinafter more fully described, illustrated in the accompanying drawings, which show the preferred embodiment of the invention and pointed out in the claim hereunto appended.

In the accompanying drawings—

Figure 1 is a vertical front elevation of a heating plant, partly in section, constructed in accordance with the invention.

Figure 2 is a top plan view thereof with parts broken away for illustrating certain details of construction.

Figure 3 is a sectional view taken on the line 3—3 of Figure 1 looking in the direction of the arrows.

2

Figure 4 is a fragmentary sectional view taken on the line 4—4 of Figure 1 looking in the direction of the arrows.

Figure 5 is a fragmentary sectional view taken on the line 5—5 of Figure 1 looking in the direction of the arrows.

Figure 6 is a sectional view taken on the line 6—6 of Figure 1 looking in the direction of the arrows.

Figure 7 is a sectional view taken on the line 7—7 of Figure 1 looking in the direction of the arrows. Similar reference characters indicate corresponding parts throughout the several views in the drawings.

Referring to the drawings in detail, A designates generally the gravity type heating plant constructed in accordance with the invention, and comprising an outer sheet metal casing or housing 10, it being sectionally set-up in any approved manner, and in this instance is of substantially rectangular shape of vertical columnar form. Centrally of the casing or housing 10 interiorly thereof, at the forward portion thereof, in vertical column-like manner, is built a lower ash pit 11, a superposed fire box 12, an upper combustion chamber 13, and a topping combustion dome or crowning head 14, respectively, the walls 15 of these being brick lined at 16. The ash pit 11 and the fire box 12 are accessible through the use of horizontally swinging doors 17 and 18, respectively, which are located at the front of the casing or housing 10, and are latched closed in any suitable manner, for example as at 19, best seen in Figure 1 of the drawings.

The fire box 12 carries therein removable grate bars 20, which may be of the group type or of the individual shaking type, and are supported in any selected manner. The lining to the ash pit 11, as well as the fire box 12 and the combustion chamber 13 are provided with air interstices 21, communicative with air ports 22 opening through the front of the housing or casing 10, and also as at 23 through the rear of the fire box 12, these being secondary air ports. It will be noted that there

is no need of regulating the flow of air through outlet interstices 21 when air enters port 22. All air entering is from without the ash pit or feed door openings, and this is a very important improvement since air entering through the ash pit becomes saturated with ash dust and clogs interstices through which it rises. The damper 24, controlled by hand lever 25 operates indirect damper 32 as shown in Figure 4. The doors 17 and 18 are provided with primary air ports 26

55 which are controlled by dampers 27 and 28, re-

spectively, best seen in Figures 6 and 7 of the drawings.

Built at opposite sides of the columnar ash pit 11, fire box 12, combustion chamber 13 and dome or crowning head 14 are vertically directed banks of radiator flues 29, which extend in a horizontal direction from the front to the back walls of the housing or casing 10, and at their upper most portions 30 upwardly converge in overhanging relation to the dome or head 14, where communicating laterals 31 open into the latter. Direct draft from the firebox is controlled by a horizontal hinge action swinging damper 32, and location of the hinge at the bottom prevents burning out or warping. The flues 29 are horizontally and vertically intersected by smoke baffles 33 and 34, respectively, supported therein. The damper 32 confronts the chimney or smoke stack outlet 35, as best seen in Figure 4 of the drawings. The flues 29 are accessible for clean-out purposes through doors 36 arranged at the front and back of the casing or housing 10. The banks of radiator flues 29 are carried deep into the housing or casing 10, and the products of combustion and smoke fumes travel horizontally and vertically in circuitous courses within the said flues 29 from the fire box and combustion chamber, downwardly and thence in an upward direction for discharge through openings 31^a into the smoke pipe 35.

About the columnar ash pit, fire box and combustion chamber, and also the banks of flues, are spaces which receive air from circulating space 37. The heated air is delivered to distributing pipes 38 (see Figure 1). 38^a are the cold air intakes between plates 39 and the casing 10.

Adjoining the space 37 and depending from the top of the casing or housing 10 at the outer sides of the banks of flues 29, and running from the front to the back of such casing or housing are spaced vertically disposed circulating hot air insulation plates 39, these being considerably removed from the bottom of the casing or housing 10, for proper air circulation.

On the top of the crowning head or dome 14 of the furnace unit is a moistener or water pan 40 which is supplied with water in any suitable manner, while arranged near the top of the casing or housing 10 outwardly of the upwardly converging portions of the plates 39 are laterally inclined supports 41 for air filters 42, and designed for filtering cold air so that the resulting heated air will be conditioned and filtered.

The plant can be fired with solid or fluid fuel and operates with equal efficiency in either case, and in the construction thereof assures a mini-

mum consumption of fuel with a maximum of heating qualities. The plant is constructed for direct or indirect draft facilities, and is of a uniform and even burning character, it being readily and easily operated and controlled.

What is claimed is:

In a hot air heating furnace, the combination, which comprises, a centrally disposed furnace unit having a dome-shaped upper end; a plurality of radiator chambers rectangular-shape in vertical and horizontal cross section parallel to and spaced from the sides of said furnace unit, said radiators having horizontally disposed baffles in the intermediate parts thereof and vertically disposed baffles spaced from the rearward ends providing horizontal and vertical passages respectively, the uppermost of said horizontally disposed baffles extending from the forward ends of the said radiators to points spaced from the vertically disposed baffles providing open areas for the downward passage of gases therein, and the lowermost of said horizontally disposed baffles extending from the lower ends of the vertically disposed baffles, providing an L-shaped transverse web in each of said radiators; the lower element of said web extending forward to a point spaced from the forward end of each of said radiators providing open areas for the downward passage of gases therein, flue connections at the forward ends of the radiators positioned above the uppermost of said horizontally disposed baffles and between the upper ends of the said radiators and the dome-shaped upper end of the furnace unit, and stack connections extending from the upper ends of the vertical passages formed by the vertically disposed baffles and merging to a common outlet.

FREDERICK WM. EICHHOLTZ.
